LINK JOINT CONNECTING ROD

Filed April 11, 1921

Patented June 12, 1923.

1,458,345

UNITED STATES PATENT OFFICE.

JOHN KONAR, OF CHICAGO, ILLINOIS.

LINK-JOINT-CONNECTING ROD.

Application filed April 11, 1921. Serial No. 460,562.

To all whom it may concern:

Be it known that I, JOHN KONAR, a citizen of the United States of America, and a resident of Chicago, in the county of Cook, State 5 of Illinois, have invented certain new and useful Improvements in Link-Joint-Connecting Rods, of which the following is a specification.

My invention relates to improvements in 10 crank operated connecting rods and the object of my invention is to afford a linkjoint between the connecting rod and the crankpin for adapting the rod and a therewith connected workhead to leap by their projectile 15 and centrifugal forces beyond the usual dead center and to return by similar forces, or with the aid of a peculiar cam attachment.

My linkjointed rod is simple, durable and 20 efficient to improve an ordinary four cycle gas engine by allowing the piston to drive its scavenging stroke into the very compression space for a better disposal of the overhot dead gases.

Fig. 1 is a side view in elevation of my 25 linkjointed connecting rod and illustrates the rod in its fully stretched and projected dead center state, as for instance at the end of the exhaust stroke with a gas engine.

Fig. 2 is a side view in elevation of my 30 linkjointed connecting rod, and illustrates the rod with a cam attachment and progressing to finish the intake stroke by clasping into the collapsed position of Fig. 3, which illustrates a ready condition for a new 35 stroke, as for instance for compression after intake with a gas engine.

Fig. 4 is a side view in elevation of my 40 linkjointed connecting rod and illustrates the rod partly extended in a transient projecting condition to reach the position of Fig. 1.

Fig. 5 is a side-view of Fig. 3, as seen from the direction of the broken line 1.

Fig. 6 is a side-view in elevation of a modification of my linkjointed connecting rod 45 and illustrates the rod in a lower dead center position, as indicated by the axis line 1.

The broken line 1 represents the longitudinal axis of a cylinder with a vertical four cycle gas engine.

50 The crank shaft 2, usually suitably mounted, has a web 3 and thereon a crankpin 4 with an orbit indicated by the arrow circle 5.

On the crankpin is journaled a box 6, from 55 which projects a linkend with two orifices 7 and 7'.

The connecting rod 8 may be attached in a usual way, in this case by a wristpin 9, to a suitable work head, as for instance to a piston of a gas engine with this my selected 60 exemplification. The crankend of the connecting rod has a loop 10 to slip between the orifices 7 and 7' for engaging the linkpin 11, that is inserted in said orifices; thereby the rod is hinged to a linkpin, that combines 65 the loop 10 with said orifices into a linkjoint to swing with said linkend on the crankpin and therewith affords to said crankend a radius of oscillation at a distance of said crankpin and thus enables the rod to leap 70 beyond the usual headward dead center terminal.

From the crankend of the rod projects towards the box 6 a heel 12, which in Fig. 3 is shown set on the box to give the connecting rod a better support on the crank pin during the compression, during the power stroke and during the first half of the exhaust stroke.

When the crankpin, ascending for the exhaust stroke as in Fig. 3, passes about 120 degrees upward travel, the high speeded piston and the connecting rod start a leap by their faster projectile force and fly away 80 from the crankpin towards the upper dead center; they distance the heel 12 from the box 6, and simultaneously upturn the linkjoint into the subsequent positions of Fig. 4 and Fig. 1. The upturning of the linkjoint is accelerated by its own centrifugal force 85

and by that of the crankend of the rod. In the transient course from Fig. 4 to Fig. 1 the crankpin wedges the link against the linkpin, prays thereby the linkpin further 90 out of the orbit 5 and insures the elevation of the connecting rod and the piston into the extreme exhaust dead center position of Fig. 1. Near the end of the exhaust stroke 95

the fast airpush behind it also helps the piston to project. By the said combined forces the connecting rod stretches its linkjoint to the full extension, as shown in Fig. 1, and aids the piston to forerun the radius 100 of the crankpin and to push into the very compression chamber for expelling from there the overhot foul gases effectively even against the resistance of a muffler, that is used with automobiles.

From the position of Fig. 1 the crankpin 110 pulls the connecting rod with a stretched out linkjoint and with ever increasing speed towards the position of Fig. 2 during about

100 degrees of the intake stroke, when the piston at its highest speed jumps in a straight course towards the lower dead center, whereto the crankpin is racing in a 5 curve. There then the gravitation and the projectile force of the piston and the tangentially inclined connecting rod combine with the centrifugal force of the lower rodend for driving the also centrifugally 10 disposed linkjoint in the direction of the arrow 13 and towards the orbit 5, so as to clasp the linkjoint into a collapse, as shown in Fig. 3; thereby the friction from the crankpin on the box 6 also helps to turn the 15 linkjoint in the direction of the arrow 13. Ordinarily the mentioned inertia forces are sufficient to collapse the connecting rod into the finished intake position of Fig. 3.

Friction, too much vacuum in the cylinder 20 or an overturned position of the engine may retard the clasping of the linkjoint; then more positive clasping means are afforded by the cam 14 and the roller 15. The cam 14 is with one side attached to the crankend 25 so as to have a side-clearance towards the web. The cam 14 is curved upward from the vicinity of the end of the heel 12 towards the axis of the rod. In parallel alignment with the crankshaft is a stud projected from 30 the web to carry the roller 15, that is suitably located to meet the cam 14. After the connecting rod reaches the position of Fig. 2, the roller 15 runs along the cam 14 and pushes it together with the linkjoint into the 35 finished intake position of Fig. 3 which is the inflexible relation of parts with my linkjoint rod during the compression stroke and during firing.

The roller and cam-action insures a speedy 40 return of the piston and a high end velocity of the intake, whereby the new all fuel charge is pneumatically rammed into density within a well ventilated space, which is a big gain, especially with engines working 45 in a rarefied atmosphere, as in aviation. By expulsion of the overhot foul gases from the compression chamber the volumetric capacity of the intake is so much increased; simultaneously the quality of the new charge is 50 improved by the absence of dilution and heat expansion through hot dead gases. The larger, cleaner, cooler and therefore denser new charge develops with the same amount of compression a much higher pressure during firing, which again improves total inflammation and combustion, is more 55 flammable to carbon deposits and thereby eliminates troubles, permits more compression without danger to pre-ignition and increases power efficiency per pound of engine 60 and per pound of fuel with a widened range for using the lower grades of fuel.

The high end velocity of the intake insures a quick completion of the filling and permits more ease in closing the intake 65

valve. Also more time and ease is gained for the closing of the exhaust valve by the quickened scavenging, that the forerunning piston produces, as indicated in Figs. 4 and 1.

On the crankend is opposite from the heel 70 12 a duplicate heel 12' and opposite from the cam 14 is a duplicate cam 14' for running the engine in a reversed direction.

When the engine has to run only in one 75 direction a modified connecting rod 8' as shown in Fig. 6 may be seated with its crankend directly on the box 6, which support improves the alignment of the rod 8' 80 in comparison to the offset heel support of the connecting rod 8. The crankend of the connecting rod 8' has a heel-like base, that is shaped to match the top of the box 6 to have thereon a broader support. From one side of the base extends a pedal towards the 85 loop 10' to engage therewith the linkpin 11, that forms with the orifices 7 and 7' a linkjoint on said linkend, whereby the pedal is adapted to swing the connecting rod with the linkend upon the crankpin. Projecting 90 from the loop 10' is a stop 16, which bears against the linkend and bars the linkjoint from an undue tilting over the dead center, when the rod 8' is in similar positions as the 95 rod 8 is in Figs. 1, 2 and 4. In Fig. 6 is also shown a cam 14' attached to the web 3 to meet a roller 15' that is pivoted near the crankend of the rod 8', which cam and roller disposition is a reversal and an equivalent 100 transposed location of the cam 14 and the roller 15.

The length of my linkjoint connecting rod in a collapsed state, taken from crankpin to 105 wristpin, is equal to the normal length of an ordinary connecting rod. By the ability to collapse from its most extended length into said normal length, the link affords flexibility to said connecting rod and therewith lost motion and latitude to skip its extending and the forcing of said piston into the compression chamber at the end of the compression stroke.

During the compression stroke with a 110 four cycle gas engine the linkjoint rod is pressed by the crank against the piston and the resistance of the compressed charge and therefore is unable to extend from the settled position of Fig. 3 to get against closed valves, as for firing, into the position of 115 Fig. 1, that shows the rod in a state of exhaust end extension and is only possible, when no compression resistance hinders the inertia of the piston and the rod. While my linkjoint rod is able to extend during the 120 exhaust stroke in combination with a four cycle gas engine for letting the piston inside the compression chamber and expel the foul gases, the main advantage of said rod resides in its ability to return during intake 125 time to the inflexible position of Fig. 3, and 130

to keep that position by automatically skipping extension entirely during the compression stroke and to stay rigid and without lost motion at the end of the compression stroke and during firing.

My crank operated linkjoint connecting rod may also be connected by the wristpin 9 or by an equivalent thereof to drive suitably guided rocker arms, rocker beams, rams, 10 hammers, chisels, knives, saws, pumpworks and the like other workheads, whereby the lost motion, afforded by the linkjoint, permits the workheads to exert their momentum on the work with a range of safety to the 15 crank, when an undue obstacle is met by the workheads, as for instance with varying work dimensions in forging. The crank movement may be inclined, horizontal or turned upside down for special purpose; the 20 length of the link may vary also.

I claim—

1. With a crank movement having a suitably guided workhead, a rotative crankshaft provided with a crankpin, a link having one 25 of its ends rotatably fitted on said crankpin, said link having near its other end a linkjoint to engage therewith the crankend of a connecting rod, a connecting rod linked with its crankend to said linkjoint and having at 30 its other end means to engage said workhead, whereby during speedy dead center transitions of the crankpin said linkjoint is free to yield and to release said connecting rod and a thereto adapted workhead for ex- 35 tending by combined inertia their travel beyond the radius of the crankpin and whereby said linkjoint also affords flexibility to said connecting rod and therewith lost motion and latitude to said crankshaft when 40 an undue obstacle is met by said workhead.

2. With a crank movement having a suitably guided workhead, a rotative crankshaft provided with a crankpin, a link having at one of its ends a journalbox and bearing therewith rotatably on said crankpin, said link having near its other end a linkjoint to engage therewith the crankend of a connecting rod, a connecting rod linked with its crankend to said linkjoint and having at its 45 other end means to engage said workhead, whereby during speedy dead center transitions of the crankpin said linkjoint is free to yield and to release said connecting rod and a thereto adapted workhead for extending by combined inertia their travel beyond the radius of the crankpin and whereby said linkjoint also affords flexibility to said connecting rod and therewith lost motion and latitude to said crankshaft when an undue 50 obstacle is met by said workhead, a heel-like side projection extending from said crank end adapted to engage said journalbox as a support to said connecting rod.

3. With a crank movement having a suitably guided workhead, a rotative crankshaft

having a web provided with a crankpin, a link having at one of its ends a journalbox and bearing therewith rotatably on said crankpin, said link having near its other end a linkjoint to engage therewith the crankend 70 of a connecting rod, a connecting rod linked with its crankend to said linkjoint and having at its other end means to engage said workhead, whereby during speedy dead center transitions of the crankpin said linkjoint is free to yield and to release said connecting rod and a thereto adapted workhead for extending by combined inertia their travel beyond the radius of the crankpin and whereby said linkjoint also affords flexibility 75 to said connecting rod and therewith lost motion and latitude to said crankshaft when an undue obstacle is met by said workhead, from said crankend protuberant towards said web a cam, located between the ends of the web and projecting from the web towards the path of said cam a stud bearing a roller and aligned to meet and to positively actuate said cam and therewith said linkjoint connecting rod into a return to their rear 80 terminal.

4. With a crank movement having a suitably guided workhead, a rotative crankshaft having a web provided with a crankpin, a link having at one of its ends a journal box and bearing therewith rotatably on said crankpin, said link having near its other end a linkjoint to engage therewith the crankend 95 of a connecting rod, a connecting rod linked with its crankend to said linkjoint and having at its other end means to engage said workhead, whereby during speedy dead center transitions of the crankpin said linkjoint is free to yield and to release said connecting 100 rod and a thereto adapted workhead for extending by combined inertia their travel beyond the radius of the crankpin and whereby said linkjoint also affords flexibility to said connecting rod and therewith lost motion and latitude to said crankshaft when an undue obstacle is met by said workhead, from said crankend protuberant towards said web a cam, located between the ends of the web and projecting from the web towards the path of said cam a stud bearing a roller and aligned to meet and to positively actuate said cam and therewith said linkjoint connecting rod into a return to their rear 105 terminal, from said crankend a heel-like sideprojection adapted to engage said journalbox as a support to said connecting rod.

5. With a crank movement having a suitably guided workhead, a rotative crankshaft provided with a crankpin, a link having at one end a journalbox and bearing therewith rotatably on said crankpin, said link having near its other end a linkjoint to engage therewith the crankend of a connecting rod, a connecting rod having with its crankend 125

70

75

80

85

90

95

100

105

110

115

120

125

130

5 a heel-like base shaped to bear upon the top of said journalbox, extending sideways from said heel-like base a pedal linked with its end to said linkjoint, at the other end of the connecting rod means to engage said workhead, whereby during speedy dead center transitions of the crankpin said linkjoint yields to release said connecting rod and a thereto adapted workhead for extending by 10 combined inertia their travel beyond the radius of the crankpin and whereby said linkjoint also affords flexibility to said connecting rod and thereby lost motion and latitude to said crankshaft when an undue obstacle 15 is met by said workhead.

20 6. In combination with a four cycle gas engine having a movable piston, a rotative crankshaft having a web and thereon a crankpin, a link having at one of its ends a journalbox and bearing therewith rotatably on said crankpin, said link having near its other end a linkjoint to engage therewith the crankend of a connecting rod, a connecting rod linked with its crankend to said linkjoint and having at its other end means to engage said piston, whereby during speedy dead center transitions of the crankpin said linkjoint is free to yield in order, first, to release said connecting rod and a thereto adapted piston for extending by combined inertia their exhaust stroke beyond the radius of the crankpin to let said piston leap inside the compression chamber and displace the exhaust residue, second, to enable said piston to return by inertia to the end of the intake stroke and, third, to afford flexibility to said connecting rod and therewith lost motion and latitude to said crankshaft to skip forcing said piston into the compression space during the compression stroke. 30

35 7. In combination with a four cycle gas engine having a movable piston, a rotative crankshaft having a web and thereon a crankpin, a link having at one of its ends a journalbox and bearing therewith rotatably on said crankpin, said link having near its other end a linkjoint to engage therewith the crank end of a connecting rod, a connecting rod linked with its crankend to said linkjoint and having at its other end means to engage said piston, whereby during speedy dead center transitions of the crankpin said linkjoint is free to yield in order, first, to release said connecting rod and a thereto adapted piston for extending by combined inertia their exhaust stroke beyond the radius of the crankpin to let said piston leap inside the compression chamber and displace the exhaust residue, second, to enable said piston to return by inertia to the end of the intake stroke and, third, to afford flexibility to said connecting rod and therewith lost motion and latitude to said crankshaft to skip forcing said piston into the compression

65 space during the compression stroke, from said crankend a heel-like sideprojection adapted to engage said journalbox as a support to said connecting rod during the compression and the power stroke and during part of the exhaust stroke. 70

75 8. In combination with a four cycle gas engine having a movable piston, a rotative crankshaft having a web and thereon a crankpin, a link having at one of its ends a journalbox and bearing therewith rotatably on said crankpin, said link having near its other end a linkjoint to engage therewith the crankend of a connecting rod, a connecting rod linked with its crankend to said linkjoint and having at its other end means to 80 engage said piston, whereby during speedy dead center transitions of the crankpin said linkjoint is free to yield in order, first, to release said connecting rod and a thereto adapted piston for extending by combined inertia their exhaust stroke beyond the radius of the crankpin to let said piston leap inside the compression chamber and displace the exhaust residue, second, to enable said piston to return by inertia to the end of the intake stroke and, third, to afford flexibility to said connecting rod and therewith lost motion and latitude to said crankshaft to skip forcing said piston into the compression space during the compression stroke, 85 from said crankend protuberant towards said web a cam, located between the ends of the web and projecting from the web towards the path of said cam a stud bearing a roller and aligned to meet and to positively actuate said cam and therewith said linkjoint connecting rod into returning said piston to the end of the intake stroke. 90

95 9. With a crank movement having a suitably guided workhead, a singular rotative crankshaft provided with a crankpin, a link having one of its ends rotatably fitted on said crankpin, said link having near its other end a linkjoint to engage therewith the crankend of a connecting rod, a connecting rod linked with its crankend to said linkjoint and having at its other end means to engage said workhead, whereby during speedy dead center transitions of the crankpin said linkjoint is free to yield and to release said connecting rod and a thereto adapted workhead for extending by combined inertia their travel beyond the radius of the crankpin and whereby said linkjoint also affords flexibility to said connecting rod and therewith lost motion and latitude to said crankshaft when an undue obstacle is met by said workhead. 100
